US0D1009812S

(12) **United States Design Patent** (10) Patent No.: **US D1,009,812 S**
(45) Date of Patent: ** *Jan. 2, 2024

(54) **CONTROL DEVICE**

- (71) Applicant: **Lutron Technology Company LLC**,
Coopersburg, PA (US)
- (72) Inventors: **Gregory Altonen**, Easton, PA (US);
Chris Dimberg, Easton, PA (US);
Jason C. Killo, Emmaus, PA (US)
- (73) Assignee: **Lutron Technology Company LLC**,
Coopersburg, PA (US)
- (*) Notice: This patent is subject to a terminal disclaimer.
- (**) Term: **15 Years**
- (21) Appl. No.: **29/883,400**
- (22) Filed: **Jan. 27, 2023**

Related U.S. Application Data

- (63) Continuation of application No. 29/809,651, filed on Sep. 29, 2021, now Pat. No. Des. 978,092, which is a continuation of application No. 29/709,557, filed on Oct. 15, 2019, now Pat. No. Des. 933,615.

CLAIM

The ornamental design for a control device, as shown and described.

DESCRIPTION

FIG. 1 is a front perspective view of a control device showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines illustrate structure or features which form no part of the claimed design.

1 Claim, 5 Drawing Sheets
